UNITED STATES PATENT OFFICE

136,398

DESIGN FOR A GOGGLE

Ernest A. Ring, West Barrington, R. I., assignor
of one-half to Francis M. Blakeney, Cranston,
R. I.

Application June 18, 1943, Serial No. 110,479

Term of patent 14 years

To all whom it may concern:

Be it known that I, Ernest A. Ring, a citizen of the United States, residing at West Barrington, in the county of Bristol and State of Rhode Island, have invented a new, original, and ornamental Design for a Goggle, of which the following is a specification, reference being had to the accompanying drawing, forming a part thereof.

Fig. 1 is a perspective view of the goggle showing my design;

Fig. 2 is a front elevational view of the same;

Fig. 3 is an end elevational view of the goggle; and

Fig. 4 is a top plan view thereof.

The essential features of my design reside in the portions shown in full lines, the head strap being shown fragmentarily in Figs. 2, 3 and 4 for convenience of illustration.

I claim:

The ornamental design for a goggle, substantially as shown and described.

ERNEST A. RING.
